UNITED STATES PATENT OFFICE.

EDWARD BRUCK, OF SPOKANE, WASHINGTON.

COMBINED HUMIDIFIER AND PALETTE ATTACHMENT.

1,414,338.

Specification of Letters Patent.

Patented May 2, 1922.

Application filed April 12, 1921. Serial No. 460,860.

To all whom it may concern:

Be it known that I, EDWARD BRUCK, a citizen of the United States, residing at Spokane, in the county of Spokane and State of Washington, have invented certain new and useful Improvements in Combined Humidifier and Palette Attachments, of which the following is a specification.

The present invention relates to an improved combined humidifier and palette attachment designed especially for use by professional and amateur painters for preserving the paints or colors in moistened condition and for economizing in the use of the paints or colors by eliminating to a great extent the waste accompanying the use of the colors or paints on the palette.

The primary object of the invention is a receptacle or box in which the colors may be stored and kept in fresh condition ready for use at any moment, and which is accessible for storing or withdrawing the paints or colors as required, and in which certain elements of the humidifier are adaptable for bodily extraction from the humidifier and direct application to the palette when ready for painting. The invention consists in certain novel combinations and arrangements of parts of the humidifier and its accessories whereby a portion of the humidifier may be converted for use with the palette when required, and, when combined with the humidifier forms one of the co-operating elements thereof for performing the required functions of a device of this character. In the accompanying drawings one complete example of the physical embodiment of the invention is illustrated, the parts being combined and arranged according to the best mode I have so far devised for the practical application of the principles of my invention.

While I shall hereinafter refer to the device as a humidifier for paints or colors, it should be understood that I do not confine myself to this use of the invention exclusively, for the invention may readily be adapted for other uses, as will be apparent.

Figure 1 is a perspective view of the box or container, the interior of which contains the novel features of the present invention.

Figure 2 is a perspective view showing the lid of the box with its humidifier attachment at the underside, and normally located within the box.

Figure 3 is a perspective view of the removable humidifier, partly broken away for convenience of illustration, and designed to form the false bottom of the box.

Figure 4 is a transverse sectional view of the humidifier with all parts in position.

Figure 5 is a perspective view of one of the trays in which the colors are retained, and stored in the box.

Figure 6 is a plan view showing a painter's palette with two of the paint trays applied thereto.

The box 1 is of rust proof metal, and rectangular and oblong in shape, but may be made of desired size and shape and be ornamented, either by its own configuration, or by the additional use of ornamental features, and is provided with a lid 2 of like material, size and shape. The lid is of special construction and embodies a chamber 3 with a bottom wall 4 perforated as shown, and the chamber is adapted to contain an absorbent material, as felt, 5. A removable, false bottom 6 is provided for the box, which is in fact a sealed, flat box with a perforated top 7 and its interior chamber 8 contains an absorbent material as 9. Thus the interior of the box 1 is provided with two humidifying members i. e. the interior of the lid and the false bottom, for moistening the air within the box, and as both these elements are removable from the box 1, it will readily be apparent that they may be properly prepared with facility and dispatch merely by immersing them in water; and then after draining off the surplus water, and drying the exterior parts, the false bottom and lid and replaced to perform their functions. The absorbent material, such as felt, will retain the water, which will slowly evaporate and humidify the air in the box 1, and the humid air of course will maintain the colors or paints within the box 1 in a moistened condition.

Preferably the paint is kept on trays as 10 and 11, which may be of aluminum or other sheet metal of the proper size and shape, and these trays are designed for use with the palette 12 through the instrumentality of the spring clips 13 on the underside of the trays that are adapted to fit over the edge of the palette in convenient position so that the paints or colors may be kept in the stalls 14 of the trays, for use when required.

When the trays are stored in the box with their stalls containing the paints or colors the humid air keeps the paints in proper moist condition and prevents drying out, 5 and it will be noted in Figure 4 that the spring clips serve to elevate the trays above the false bottom or humidifier in order that the perforated top of the false bottom will not be closed, and to permit free movement 10 of the humidified air up past the trays into the body of the box 1. The resiliency of the clips 13 permits the ready and facile attachment and detachment of the trays to and from the palette, and maintains the trays in 15 position for use while on the palette.

In Figure 6 the palette is illustrated as equipped with the trays and ready for use, a short tray being employed at one end and a longer tray attached to one of the sides 20 of the palette. The different colors or paints are placed in their respective stalls and the colors mixed, as usual, on the palette, but it will be noted that only the colors desired for immediate use and the 25 quantity desired for immediate use, are placed on the palette, and consequently there is comparatively little loss in materials when the palette is cleaned up, for the reason that the stock of colors is kept in the stalls and 30 the trays detached and stored away in the box 1 for keeping in the humid atmosphere in the box. In this manner not only is economy secured in the use of materials, but a comparatively clean and sanitary outfit 35 is preserved, and comparatively little time is lost in cleaning the palette, for the reason that only the quantity of paints or colors for

immediate use are placed directly on the palette.

Care may be taken of the brushes also of 40 the brushes, when not in use, by depositing them in the box before the trays are placed therein, and then laying the trays on top of the brushes, with the same beneficial effects on the brushes as are attained for 45 the paints or colors.

The different parts of the device are made of rust-proof metal, and the box should of course be substantially air tight in structure to prevent escape of the humid atmosphere 50 and to prevent ingress of dust.

Having thus fully described my invention, what I claim as new and desire to secure by Letters Patent is—

1. The combination in a box as described 55 having a close-fitting lid and a hollow, false bottom, removable, and containing absorbent material, of trays having paint stalls as described, and clips on the underside of said trays resting on the false bottom for elevating the trays to permit circulation of humid air.

2. The combination in a box having a close fitting lid provided with an interior humidifying member, a removable false bottom containing an absorbent material and fashioned with a perforated top, of a tray having paint stalls, and clips on the under side of said tray resting on the perforated top for elevating the tray to permit circulation of 60 humid air.

In testimony whereof I affix my signature.

EDWARD BRUCK.
